UNITED STATES PATENT OFFICE.

RAY H. MANSON, OF ELYRIA, OHIO, ASSIGNOR TO THE DEAN ELECTRIC COMPANY, OF ELYRIA, OHIO, A CORPORATION OF OHIO.

ELECTRICAL SWITCH.

No. 926,951.

Specification of Letters Patent.

Patented July 6, 1909.

Application filed February 28, 1907. Serial No. 359,904.

To all whom it may concern:

Be it known that I, RAY H. MANSON, a citizen of the United States, residing at Elyria, in the county of Lorain and State of Ohio, have invented certain new and useful Improvements in Electrical Switches, of which the following is a specification, reference being had therein to the accompanying drawing.

10 My invention relates to electrical switches, and particularly to those having a group of contacts or other operative parts, whose condition or relations may be changed by the manipulation of a handle or similar device. 15 In most cases the operative parts are mounted as a unit within a suitable casing, and the handle or other actuating element projects from the casing. The projection of this element from the casing as well as the mode of 20 its insertion and removal and of the assembling of the switch, are frequently productive of embarrassment not only to the designers, but to those who are afterward called upon to assemble and to handle, pack, 25 and unpack the complete pieces of apparatus.

The form of switch in which my invention is shown and described as embodied, for the purpose of this application, is that used in connection with subscriber's telephone outfit, and particularly with so-called "wall sets". Its mode of adaptation to other forms will be apparent to those skilled in the art without specific description.

My invention has for its object the design 35 of a switch in which the actuating element whether a handle as used in many forms of switch, or a hook lever as used in telephone sets, may readily be detached from and attached to the operative parts of the switch 40 without otherwise disturbing their relations or arrangement.

In order to attain my object I provide a 45 fixed pivot for the actuating element or lever, which serves as a fulcrum and with which the lever engages by means of a notch or recess. Preferably between the point of application of power and the fulcrum of the lever, I provide a yielding retaining device acting to maintain the lever in engagement with its 50 fulcrum and in a direction opposed to that of the operating power. As long as this yielding device retains its resilience, the switch will operate without danger of displacing the lever, while the latter may be detached from 55 the fulcrum at any time by suitable compres-

sion of the yielding device. The points of application, of power and of the opposing yielding device may be shifted with respect to the fulcrum according to the order to which the lever belongs. The extent of 60 movement of the lever is immaterial, as long as the retaining pressure follows throughout the amplitude of movement to maintain the engagement of the lever and the fulcrum. The yielding device, as I have called it, may 65 be reduced to a latch engaging the pivot or fulcrum, in which case it is not essential that it should exert pressure directly in opposition to the power, so long as it retains the lever in engagement with its pivot. 70

In the telephone switch hereinafter described, the actuating element is the hook lever, its fulcrum is the ordinary pivot post on the switch base, and the yielding device is the actuating spring which tends to throw up the 75 lever when the telephone receiver is removed from the hook. By employing the actuating spring as the retaining device it is given a double function, and the parts are reduced to the utmost simplicity, no change being required as a matter of fact except the cutting 80 out of one side of the pivot bearing in the lever to form a notch.

By means of my invention, the embarrassments to which I have referred are entirely 85 obviated. The opening in the casing through which the operating lever must extend can be made small and inconspicuous, and the lever may be removed except when the instrument is actually in use, whereby an 90 annoying external projection is disposed of, packing cases may be made smaller, and the risk of damage to an instrument in handling or during shipment is considerably lessened.

My invention is better illustrated in the 95 drawing forming a part of this specification to which reference is made.

The cabinet C ordinarily used to contain the telephone apparatus at a substation has located therein a base B, from one end of 100 which a bracket b¹ projects for the purpose of supporting a pin P. The bracket b¹ also supports in the manner indicated switch springs s, s¹, adapted to control circuits of the telephone apparatus in a manner well 105 known. The pin P is adapted to engage a hook h³ formed on the right hand end of a receiver hook H, which extends through an opening c¹ in the side of the cabinet C. An escutcheon plate c is provided on the outside 110

of the cabinet to cover the opening c^1 , a slot being formed in the plate c to just afford a sufficient clearance for the receiver hook H so that it may move vertically to control the 5 switch springs s and s^1 . The left hand end of the receiver hook H is formed in the customary manner and consists of two jaws h adapted to support the receiver. The base 10 B has secured thereto a spring S, to the upper per and right hand end of which a block h^2 is secured. This block h^2 extends from the spring S to the under side of the hook H, as a result of which when the receiver is not in place on the jaws h the hook H is moved to 15 its upper position by the operation of the spring S. The contact spring s^1 is secured to the block h^2 , which is of insulating material, as a result of which when the hook H is moved downward, the switch springs s and 20 s^1 are separated, and when the hook H is moved upward by the spring S the contact springs s and s^1 are brought together.

The hook h^3 which engages the pin P is formed on the right hand of the receiver 25 hook II, in order that the receiver hook may be removed from the pin P and from the cabinet by depressing the receiver hook within the cabinet sufficiently to disengage the right hand end h^3 from the pin P. After such 30 disengagement the receiver hook may be withdrawn from the cabinet to the left through the opening c^1 and the escutcheon plate c . A stop b^3 secured to the base B is provided in order to limit the upward motion 35 of the spring S when the receiver hook H is removed from the pin P.

It is thought that from the description of the arrangement of parts just indicated the 40 operation of the device is apparent to those familiar with telephone practice and that therefore further description of the operation of the mechanism is not needed:

While I have shown my invention in the particular embodiment herein described, I 45 do not, however, limit myself to this exact construction, but desire to claim any equivalent construction that will suggest itself to those skilled in the art.

Having thus described my invention, what I claim and desire to secure by Letters Patent is:

1. In a hook switch for effecting circuit changes in a telephone set, a box or housing for the apparatus of the set, a base supported in the box, a bearing on such base, switching 55 springs mounted in the box for changing circuit conditions as desired, a switch hook adapted to removably engage such bearing and to project outside of the box to support a receiver, and a returning spring having its 60 free end mechanically connected to but insulated from the circuit changing springs.

2. In a hook switch for effecting circuit changes in a telephone set, a box or housing for the apparatus of the set, a base supported 65 in the box, a bearing on such base, switching springs mounted in the box for changing circuit conditions as desired, a switch hook adapted to removably engage such bearing and to project outside of the box to support 70 a receiver, and a returning spring mechanically connected to the circuit changing springs, such connecting means constituting means for insulating such switch hook and such returning spring from the circuit changing 75 springs.

3. In a hook switch for effecting circuit changes in a telephone set, a box or housing for the apparatus of the set, a base supported in the box, a bearing on such base, switching 80 springs mounted in the box for changing circuit conditions as desired, a switch hook adapted to removably engage such bearing and to project outside of the box to support a receiver, and a returning spring having its 85 free end connected to the circuit changing springs, such returning spring independent of the circuits through such circuit changing springs.

In testimony whereof I affix my signature 90 in presence of two witnesses.

RAY H. MANSON.
